CIGARETTE OR CIGAR CASE

Hans Schowanek, Albrechtsdorf, Czechoslovakia

Application September 14, 1932, Serial No.
633,159. Renewed October 2, 1934. In Czechoslovakia June 20, 1932

2 Claims. (Cl. 206—41)

This invention relates to a cigarette or cigar case, which is constructed in such a manner that it is composed of a plurality of elongated elements, which are provided on their abutting faces with grooves of semi-circular cross section and extending in longitudinal direction. These elements are transversely threaded at their ends on a flexible element by means of which the plugs along the grooves are at the same time held.

To insert or remove a cigarette or cigar, the corresponding elongated elements are opened by bending the flexible elements at this point.

An embodiment of the invention is illustrated by way of example in the accompanying drawing in which:

Fig. 1 shows the case in side elevation.

Fig. 2 is a cross section of Fig. 1.

Fig. 3 shows the case in perspective view.

According to the invention the case is composed of elongated elements having in their abutting faces grooves *b* of semi-circular cross section. The two outer elements *a*¹ have each only one groove which is provided on the inner face. These grooves are closed at their upper and lower ends by plugs *c* which act at the same time as hinges so that a slipping in longitudinal and also lateral direction is prevented. The elongated elements *a* are held together by means of flexible elements *d*, for example, rubber cords or spiral springs extending transversely through the ends of the elements *a*. The plugs *c* are likewise threaded on the flexible elements *d*. The cigarettes or cigars are inserted in the spaces formed by the grooves *b* of the abutting elongated

elements by bending the flexible elements as shown in Fig. 3. For removing a cigarette or cigar the flexible elements are bent in the opposite direction to that shown in Fig. 3, so that the cigarette or cigar in the space at which the elements *d* are bent drops out.

The outer surface of the case may be provided with printed advertising matter without departing from the scope of the invention.

I claim:

1. A cigarette or cigar case, comprising in combination a plurality of elongated elements arranged side by side and each having a longitudinal groove in each of its lateral sides forming with the groove of the adjacent element a cylindrical compartment, and flexible elements uniting said elongated elements each of said elongated elements adapted to be turned against the action of said flexible elements on one of its points of contact with its adjacent elongated element to open the compartment formed between these two elongated elements.

2. A cigarette or cigar case as specified in claim 1, comprising in combination with the flexible elements and the groove elongated elements each forming with its adjacent elements, two cylindrical compartments, plugs one in each of the ends of each of said cylindrical compartments between each two elongated elements adapted to serve as pivots for the mutual turning of said elongated elements, and held in position by said flexible elements extending transversely therethrough.

HANS SOWANEK.
